MANUFACTURE OF NAPHTHALENE

Aristid V. Grosse and William J. Mattox, Chicago, Ill., assignors to Universal Oil Product Company, Chicago, Ill., a corporation of Delaware

No Drawing. Application June 28, 1937,
Serial No. 150,760

3 Claims. (Cl. 260—668)

This invention relates more particularly to the manufacture of naphthalene by reactions involving dehydrogenation and cyclization of aliphatic hydrocarbons.

5 In a more specific sense it is concerned with the application of the foregoing types of reactions to aliphatic hydrocarbons of a definite configuration having 10 carbon atoms in straight chain arrangement such as normal decanes or 10 decenes or the alkylated homologs thereof.

The present processes for the production of naphthalene are principally confined to those involving the high temperature cracking of oils and tars for the production of lighter products 15 such as gasoline, benzol, and light naphthas, the naphthalene being produced in relatively small amounts and recovered in the gas-washing systems. The present process provides for the manufacture of this valuable compound by a 20 specific process in which naphthalene formation is the principal reaction and in which high yields of relatively pure naphthalene are produced. The decanes or similar charging stocks submitted to the reactions of the process may be produced 25 by any convenient method such as, for example, by the fractionation of a paraffinic gasoline to produce a cut containing relatively high percentages of n-decanes.

In one specific embodiment the present invention 30 comprises the production of naphthalene by subjecting n-decane to temperatures of the order of 500–650° C. for a period of time of from approximately 0.1–15 seconds under atmospheric pressure while in contact with catalysts comprising active aluminum oxide supporting minor 35 percentages of chromium sesquioxide.

In further embodiments, n-decenes or the alkylated derivatives of aliphatic hydrocarbons containing 10 carbon atoms in straight chain arrangement may be substituted for n-decane and alkyl derivatives of naphthalene also produced. In these alternative operations the temperature and time of contact with the catalysts may be 40 varied to accommodate the varying molecular 45 weights and structures of the charging materials.

The reactions involved in the present process are typified by the following structural equation:

The above equation does not indicate any possi-

ble mechanisms involving the existence of intermediate products since several possibilities exist although they are hard to check by well-defined analytical procedure. For example, it is possible that partial dehydrogenation of the decane occurs with the primary formation of a single ring with alkyl substitution since separate experiments have indicated that naphthalene is also producible by the dehydrogenating treatment of butyl benzols, which may therefore exist as intermediate products. Furthermore, the above equation does not take into account the known facts that there are a considerable number of side reactions which result in the formation of both aliphatic and cyclic hydrocarbons of both 5 higher and lower molecular weight than naphthalene. Again if instead of n-decane or n-decenes, alkyl substituted homologs are employed, there is some production of alkyl derivatives of naphthalene. However, there is at all times a 10 substantial and worthwhile production of the desired main product so that the process is of a 15 practical and commercial character.

According to the present invention, the preferred catalysts for selectively dehydrogenating 20 and cyclizing decanes to produce naphthalene have been evolved as the result of a large amount of investigation with catalysts having a general dehydrogenating action upon various types of hydrocarbons such as, for example, those which 25 are encountered in the fractions produced in the distillation and/or pyrolysis of petroleum and other naturally occurring hydrocarbon oil mixtures. Catalysts whose preparation and properties will be presently described are particularly 30 selective when carefully regulated conditions are employed and are characterized by long life and 35 relatively easy regeneration after they have become carbonized.

It should be emphasized that in the field of 40 catalysts there have been very few rules evolved which would enable the prediction of what materials will catalyze a given reaction. Most of the catalytic work has been done on a purely empirical basis, though at times certain groups 45 of elements or compounds have been found to be more or less equivalent in accelerating certain types of reactions. For example, the noble metals, platinum and palladium, have been found to be effective in dehydrogenating reactions, particularly in dehydrogenating naphthenes to form aromatics, but these metals are expensive and easily poisoned by traces of sulfur so that their use is considerably limited in petroleum hydrocarbon reactions.

The preferred catalysts consist of activated aluminum oxide (preferably slightly alkalized) supporting less than 15% and preferably about 5% of chromium sesquioxide. It is essential to the preparation of these active and selective catalysts for dehydrocyclization reactions that this aluminum oxide possess certain structural characteristics permitting the maintenance of a stable deposit of chromium sesquioxide on its surface which is essentially undisturbed under the conditions of operation and when regenerating by burning off carbonaceous deposits with air or other oxygen-containing gas mixtures. Aluminum oxide which is generally preferable as a base material for the manufacture of catalysts for the process may be obtained from some natural aluminum oxide minerals or ores such as bauxite or carbonates such as Dawsonite by proper calcination, or it may be prepared by precipitation of aluminum hydroxide from solutions of aluminum sulfate, nitrate, chloride, or different other salts, and dehydration of the precipitate of aluminum hydroxide by heat. Usually it is desirable and advantageous to further treat it with air or other means to activate it prior to use.

Two hydrated oxides of aluminum occur in nature, to wit, bauxite having the formula $Al_2O_3 \cdot 2H_2O$ and diasporite having the formula $Al_2O_3 \cdot H_2O$. Of these two minerals only the corresponding oxide from the bauxite is suitable for the manufacture of the present type of catalysts and this material in some instances has given the best results of any of the base compounds whose use is at present contemplated. The mineral Dawsonite having the formula

is another mineral which may be used as a source of aluminum oxide, the calcination of this mineral giving an alkalinized aluminum oxide which is apparently more effective as a support in that the catalyst is more readily regenerated after a period of service. Alumina in the form of powdered corundum is not suitable as a base.

It is best practice in the final steps of preparing aluminum oxide as a base catalyst to ignite it for some time at temperatures within the approximate range of from 600-750° C. This does not correspond to complete dehydration of the oxide but gives a catalytic material of good strength and porosity so that it is able to resist for a long period of time the deteriorating effects of the service and regeneration periods to which it is subjected.

Our experiments have further disclosed that in the presence of the preferred selective catalysts whose preparation has just been described, there is a relatively narrow range of conditions which are optimum for producing commercial yields of

naphthalene. The temperature should be comprised within the range of 500-650° C. at atmospheric pressure and the time during which the vapors of n-decane are in contact with the granular catalytic materials should be varied according to the temperature employed. At 500° C. times should be from 10-15 seconds while at 600° C. it should be considerably shorter, of the order of from 0.1 to 2.0 seconds. Under these conditions there is about a 25% yield of naphthalene based on the weight of the n-decane charged. There is also a production of considerable yields of butyl benzols and methyl-propyl benzols to an extent of 50-75% of the n-decane charged. By a proper fractionation and segregation of the products, therefore, recycle material is available so that in this type of operation the ultimate yield of naphthalene may be as high as 50%.

The following example is introduced to indicate the yields and character of the product produced by the application of the present process although not with the intent of unduly limiting its scope.

n-decane was vaporized at atmospheric pressure and passed over a granular catalyst comprising approximately 96% activated aluminum oxide and 4% chromium sesquioxide at a temperature of approximately 500° C. (932° F.) and a rate of flow was employed which permitted a time of contact of 15 seconds. In a single pass a 25% yield by weight of naphthalene was produced, the product melting at 80.1° C. By recycling of unconverted decane and a fraction comprising a mixture of butyl benzols, the ultimate yield of the desired naphthalene was 35 brought to 50% by weight of the n-decane charged.

The foregoing specification and example have sufficiently described and illustrated the character of the present invention and the results obtainable thereby although neither section is intended to be unduly limiting.

We claim as our invention:

1. A process for the production of naphthalene from aliphatic hydrocarbons having 10 carbon atoms in straight-chain arrangement, which comprises dehydrogenating and cyclizing the aliphatic hydrocarbon by subjection to a temperature of the order of 500 to 650° C. for a period of about 0.1 to 15 seconds, in the presence of 45 catalytically active aluminum oxide containing a relatively small amount of chromium sesquioxide.

2. The process as defined in claim 1 further characterized in that said aliphatic hydrocarbon comprises n-decane.

3. The process as defined in claim 1 further characterized in that said aliphatic hydrocarbon comprises n-decene.
